WINDOW SASH CONSTRUCTION

Filed Nov. 4, 1925

UNITED STATES PATENT OFFICE.

OLIVER M. EDWARDS, OF SYRACUSE, NEW YORK, ASSIGNOR TO THE O. M. EDWARDS COMPANY INC., OF SYRACUSE, NEW YORK, A CORPORATION OF NEW YORK.

WINDOW-SASH CONSTRUCTION.

Application filed November 4, 1925. Serial No. 66,728.

This invention relates to window sash construction, and has for its object a window construction in which the sash is readily removable and replaceable on account of the window guides being removable as a unit with the sash and also a construction in which a light, sheet metal hollow sash is stiffened by the removable guides.

The invention consists in the novel features and in the combinations and construction hereinafter set forth and claimed.

In describing this invention, reference is had to the accompanying drawing in which like characters designate corresponding parts in all the views.

Figure 1 is a fragmentary elevation of a window construction embodying my invention.

Figure 2 is a sectional view on line 2—2, Figure 1.

Figure 3 is a modified form of parts seen in Figure 2, some of the parts shown in Figure 2 being omitted.

Figure 4 is an enlarged fragmentary isometric view of this window construction.

This window construction comprises, generally, a frame, a sash and window guides; the guides and the sash fitting one within the other and being removable as a unit upon movement of the sash and guide in a direction at an angle to the plane of the sash, and the guide and the frame having means which interlock upon such movement of the guide and sash, and which determine the proper alignment or position of the guide, the guide having means located outside the sash for securing it to the frame.

The window frame may be of any suitable form, size and construction. In Figure 2 the window frame is shown as covered by an outer plate or sheathing 2 which may be the outer steel sheathing of a railway car or of a bus, and in Figure 3 the frame is shown as of wood, and having lips as shown at 3 along the sides of each window opening. The construction shown in Figure 2 is illustrative of the modern construction of vehicles or railway cars, and that shown in Figure 3 of the old construction of railway cars, 4 designates the sash, 5 are the guides.

The sash is made up of hollow, sheet metal stiles and rails the stiles being in the form of a channel open at the edge of the sash, and also the ends of the rails which lap the ends of the stile being formed with channels as at 7 aligned with the channels 6.

The guides 5 and the stiles fit one within the other so that the guides brace the hollow, sheet metal stiles, and as here shown the guides 5 extend into and fit the channels 6 and 7, and stiffen the walls thereof.

The means by which the guides are interlocked with the frame and are removable by a rectilinear movement of the sash at an angle to the plane of the sash, comprises a gage plate 8 along each side of the frame at the edge of the sash and means on the guide coating with plate. The gage plate along one lengthwise edge has an inwardly facing channel 9, and the guide is formed with a base flange 10 along one side thereof extending into such channel 9, and is also formed with a base flange 11 on the other side thereof forlapping the outer margin of the gage plate 8. The flange 11 is also formed with a lip 12 for abutting against the end edge of the plate 8. The guide thus has stop surfaces at 13 and 14 at opposite edges thereof for engaging complementary surfaces on the gage plate when the guide stop is properly aligned or located relatively to the gage plate 8.

In addition to the interlocking with the gage plate 8 means is provided for securing the guide 5 to the frame, this means being shown as one or more screws 15 extending through holes in the flange 11, and in the plate 8; these holes coming into alignment only when the guide is properly aligned or located relatively to the plate 8, that is when the surfaces 13 and 14 abut against the inner and outer edges of the gage plate.

The gage plate normally forms a part of the sash unit; that is it is furnished or shipped as a unit with the sash and guide, and when such unit is received by the car manufacturer the workman first places the gage plate 8 on the window frame and, in the construction shown in Figures 2 and 4, merely aligns the outer edge of the gage plate with the outer face of the plate 2.

When this construction is used on old work, the gage plate 8 is merely abutted against the lip 4, Figure 3. In either case the gage plate is secured into position after being properly located by screws 16. The sash is also provided with suitable sash locks which coat with the guides; these sash locks being designated 17 and including movable locking members 18, which move through holes in the front walls of the stiles 5 into engagement with the guides 5 within the stiles.

The sash lock and the sash construction forms no part of this invention.

15 This window construction is compact and makes a very fine appearance. Also the sash can be removed from, and placed in, the frame with minimum effort and time, and with the exercise of no skill whatever, as 20 it is necessary to manipulate but two or three screws for each guide. Also the sash and guides are slipped or fitted into the window opening in interlocking engagement with the gage plates, in a natural way analogous to the sliding of a bureau drawer in 25 position.

What I claim is:—

1. In a window construction the combination of a frame, a sash, a guide for the sash 30 and along which the sash slides; the guide and sash interlocking one within the other at the edges of the sash and being removable from the frame as a unit and means for securing the guide while interlocked with the sash to the frame.

2. The window construction of claim 1 in which the frame and the guide are provided with means for interlocking upon a movement 40 of the guide and sash relatively to the frame in a direction at a right angle to the plane of the sash.

3. The window construction of claim 1 in which the frame is provided with means 45 formed with an inwardly facing, lengthwise groove, and the guide is formed with a base flange on one side thereof movable into the groove to interlock in the groove, and is also formed with the base flange on its other side for securement to the frame.

50 4. The window construction of claim 1 in which the frame is provided with a gage plate formed with a lengthwise groove along one edge facing inwardly and the guide is formed with a base flange on one side thereof for interlocking in the groove, and with a base flange on the other side thereof for resting on the gage plate and fastening members through the latter base flange and the gage plate.

60 5. The window construction of claim 1 in which the frame is provided with a gage plate formed with an inwardly facing, lengthwise groove along one edge thereof, and the guide is formed with a lengthwise base flange on one side thereof interlocking

in the groove and a lengthwise base flange on the other side thereof lapping the gage plate, the latter flange having a lip for abutting against the edge of the gage plate when the former flange is entered to full extent into 70 said groove, and fastening means extending through the latter flange and the gage plate.

6. The window construction of claim 1 in which the sash includes a hollow, sheet metal stile in the form of a channel open 75 at the edge of the stile, and the guide extends into the stile and fits the opposing walls of the channel to stiffen the same.

7. A window construction comprising a frame, a sash consisting of thin, sheet metal 80 hollow members of comparatively narrow width, in the form of a channel open at the edge of the sash and a window guide projecting into and filling each channel to stiffen the sash; each guide and the window 85 frame having means for interlocking upon movement of the sash and guide as a unit in a direction of an angle to the plane of the sash, and a means located outside of the sash for securing the guide to the frame. 90

8. A window construction comprising a frame, a sash having comparatively light, hollow, sheet metal members and guides for the sash; each guide and a contiguous member of the sash slidably fitting one within 95 the other whereby the sash is stiffened by the guide and the guide and the frame having means for interlocking upon a movement of the sash and guide as a unit at an angle to the plane of the sash, and means located 100 outside of the sash for securing the guides to the frame.

9. The window construction of claim 8 in which the guide extends into and substantially fits the contiguous sash members. 105

10. A window construction comprising a frame, a sash and a window guide, the guide and frame having means for interlocking upon a movement of the guide in a direction 110 of an angle to the plane of the sash and thereby securing the guide to the frame.

11. A window construction comprising a frame, a gage plate, extending along each side of the frame, a window guide, the guide and the gage plate having means for interlocking upon movement of the guide in a direction at an angle to the plane of the sash, and the guide and the gage plate having abutting surfaces located on opposite 115 sides of the guide, and arranged to engage 120 when the guide is fully engaged with the gage plate.

12. The window construction of claim 11 in which the interlocking means on the gage plate and the guide comprises an inwardly 125 facing channel on the gage plate and an outwardly extending base flange on the one side guide for entering the channel, and in which the guide is formed with a base flange on the opposite side thereof for resting on the 130

gage plate, and through which fastening members are passed through alined holes in the latter flange and the gage plate.

13. The window construction of claim 11 in which the guide and the gage plate are formed with alined holes located outside the sash and arranged to come into alignment when the guide is interlocked with the gage plate in proper relation thereto.

14. The window construction of claim 1 in which the frame is provided with a gage plate formed with a lengthwise groove along one edge facing inwardly, and the guide is formed with a base flange on one side thereof for interlocking in the groove and with a base flange on the other side thereof for overlapping the gage plate, the latter flange having a lip for abutting against the edge of the gage plate when the former flange is entered to full extent into the groove, the gage plate and the latter flange having holes arranged to come into alignment when the

lip abuts against the edge of the gage plate and fastening members extending through the alined holes.

25

15. A window construction comprising a frame, a gage plate extending along the side of the frame, a window guide, the guide and the gage plate having means for interlocking upon movement of the guide in a direction at an angle to the plane of the sash, the guide having a flange on one side thereof provided with a lip for abutting against the edge of the gage plate, and the plate and said flange having holes arranged to come 35 into alignment when the lip abuts against the plate, and fastening means extending through the aligned holes.

10
35
40

In testimony whereof, I have hereunto signed my name, at Syracuse, in the county of Onondaga, and in the State of New York, this 29th day of October, 1925.

OLIVER M. EDWARDS.
